FIG. 4

FIG. 5

John Schorr INVENTOR.

BY

G. G. Bush ATTORNEY.

UNITED STATES PATENT OFFICE.

JOHN SCHORR, OF DAVENPORT, IOWA.

OPERATING MEANS FOR DOORS.

Application filed March 16, 1922. Serial No. 544,097.

To all whom it may concern:

Be it known that JOHN SCHORR, a citizen of the United States of America, residing at Davenport, in the county of Scott and State of Iowa, has invented certain new and useful Improvements in Operating Means for Doors, of which the following is a specification.

My invention relates to improvements in apparatus for opening, closing and fastening doors for garages and other structures.

The objects of my invention are, first, to provide an apparatus by the use of which the driver of an automobile may open the doors of a garage to drive into it without getting out of his car and may close the doors after driving out of the garage, without getting out of the car; second, to provide an apparatus which will automatically lock the doors in open or closed position; third, to provide a simple, cheaply manufactured and easily operated locking device adaptable for use upon doors and other moving objects.

I attain these objects by the mechanism illustrated in the accompanying drawings, in which—

Figure 1 is a top or plan view of a garage embodying my invention, but with the roof removed; Fig. 2 is a side elevation of the operating post; Fig. 3 is an enlarged detail of the locking apparatus, showing a plan view thereof; Figure 4 is an edge view of the locking apparatus; Fig. 5 is a detail plan view of the locking apparatus showing one of the bolts or latches retracted from its locked position; Sections A—A and B—B, are cross-sections upon the lines AA and BB of Figure 3, respectively.

My invention comprises links, 4, each of which has one end pivoted at 5 to an operating lever, 6, and its opposite end pivoted in a suitable socket, 3, secured to a door, 2, of the garage.

The operating lever, 6, is fulcrumed at 7 upon a suitable support, 7^a, which may be a timber secured to joists or rafters, 29, of the garage or in any other suitable manner. The support, 7^a, should be secured in a position which would allow the travel of the pivot, 5, to occur as near midway of the garage from side to side as circumstances permit.

A semi-circular rack, 8, preferably of band iron or other suitable material, is secured to the support, 7^a, and provided with

notches, 9 and 10, adapted to receive and engage the inner ends of the bolts, 11 and 12, respectively. The notches, 10 and 9, are located at points upon the rack, 8, which approximate the extreme travel of the lever, 6, so that when the doors are fully open or fully closed, the notches, 10 and 9, will engage the locking bolts, 11 and 12, respectively.

A head, 25, is secured to the end of the lever, 6, opposite to the pivot, 5. The head provides bearings, 23 and 24, for the bolts, 11 and 12. The lower end of the bolts, 11 and 12, are preferably formed square, to fit in the square holes or sockets, 24 and prevent turning. The opposite ends of the bolts, 11 and 12, are preferably round so as to slide readily in the openings, 23.

A compression spring, 22, is mounted upon each of the bolts, 11 and 12, one end of which bears against the outer portion of the head and the other end of which bears against a shoulder formed upon the bolt so that the expanding action of the spring will drive the bolts, 11 and 12, into their respective notches, 10 and 9, when in proper position therefor.

An oscillating or rocker bar, 13, is pivoted to the head, 25, and provided with an opening, 14, opposite the pivot to permit the attachment of an operating cable, 15. The ends of the oscillating or rocker bar, 13, are provided with openings, 13^a, to receive links, 11^a and 12^a, respectively. The inner ends of these links are suitably secured to the upper ends of the bolts, 11 and 12, and the outer ends are provided with heads, 21 and 20, to secure them to the oscillating or rocker bar, 13.

The lever, 6, is preferably formed of two iron bars, as shown in Figure 4.

A cable, 15, is secured to the oscillating or rocker bar, 13, by passing through the hole, 14, or any other suitable method and passes over or around a sheave or pulley, 16, secured on the side of the garage and thence out through suitable openings above the garage door to and over pulleys, 17, suitably secured to a post, 19, and down and around a second pulley, 18, secured to the post, 19, a suitable distance below the pulleys, 17.

In the operation of my device, when the doors are shut as shown in solid lines in Figure 1, the left hand line of the cable shown in Figure 2, is pulled downward.

This pulls the oscillating bar, 13, toward the pulley, 16, and as the oscillating bar rocks on its pivot, it raises the link, 11^a, thus pulling the bolt, 11, out of the notch, 10, and unlocking the doors. The continued pull on the cable then carries the head and the end of the lever, 6, to which it is secured, around to the position shown in dotted lines in Figure 1, and when it reaches 10 that position, the bolt or latch, 12, drops into the notch, 9, and locks the doors in the open position and also locks the lever, 6, against further movement toward the pulley, 16.

15 This locks the doors against being blown shut by the wind and the car can then be driven into the garage safely. Upon driving the car out of the garage, the driver can pull the right hand cable as shown in 20 Figure 2, downward, which will reverse the movement of the rope, unlatch the bolt, 12, from its notch, 9, carry the head of the lever, 6, around to the closed position shown in solid lines in Figure 1 and as the bolt, 25 11, drops into the notch, 10, it will lock the doors in closed position and they will remain locked until released by again pulling the rope or cable, 15.

Short pieces of rope may be attached to 30 the cable, 15, at appropriate places inside of the garage, so that the doors can be opened or closed from the inside of the garage as well as from the outside and additional means may be provided for locking 35 the lever, 6, in the closed position which can only be operated from inside the garage or the doors may be secured by the ordinary hasp and padlock or other suitable means on the inside of the garage.

40 It is obvious that this device, with slight modifications, can be used for sliding doors, which I have illustrated in an additional application for patent which I am filing in connection herewith and that this form of 45 lever movement may be adapted to a considerable variety of other purposes; also that the locking and unlocking mechanism may be applied to a large variety of levers and utilized for many different purposes.

50 The form, size, proportions and position of the different parts of my invention may be varied to suit the requirements of each particular case as occasion arises.

I claim:

55 1. In an apparatus for opening and closing doors, the combination with links pivoted to the doors, of a cable, a lever fulcrumed intermediate its ends and having one end pivoted to the ends of the links opposite 60 the doors and its opposite end secured to the cable, and means intermediate the cable and the lever adapted to lock the doors in open or closed position.

65 2. In an apparatus for opening and closing the door of a building, a support, an

operating lever fulcrumed thereon, a link having one end pivoted to the door near the top thereof and its opposite end pivoted to one end of the operating lever, a notched rack secured to the support, a head secured to one end of the operating lever carrying a latch adapted to enter and engage the notches in the rack. 70

3. In an apparatus for opening and closing the doors of a building, a support, an operating lever fulcrumed thereon, links each having one end pivoted to the doors, near the top thereof and its opposite end pivoted to one end of the operating lever, a notched rack secured to the support, a head secured to one end of the operating lever carrying a plurality of latches adapted to enter and engage the notches in the rack. 75

4. In an apparatus for opening and closing the door of a building, a support, an operating lever fulcrumed thereon, a link having one end pivoted to the door near the top thereof and its opposite end pivoted to one end of the operating lever, a rack secured to the support, a head secured to one end of the operating lever carrying a bolt or latch adapted to engage the rack, and means for engaging and disengaging the latch from the rack. 80

5. In an apparatus for opening and closing the doors of a building, a support, an operating lever fulcrumed thereon, links each having one end pivoted to the doors near the top thereof and its opposite end pivoted to one end of the operating lever, a rack secured to the support, a head secured to the operating lever carrying a plurality of latches adapted to engage the rack, and means for engaging and disengaging the latches from the rack. 85

6. In an apparatus for opening and closing the door of a building, a support, an operating lever fulcrumed thereon, a link having one end pivoted to the door near the top thereof and its opposite end pivoted to one end of the operating lever, a rack secured to the support, a head secured to the operating lever carrying a latch adapted to engage the rack, a cable secured to the head, and means operable by the cable for disengaging the latch from the rack. 90

7. In an apparatus for opening and closing the doors of a building, a support, an operating lever fulcrumed thereon, links each having one end pivoted to the doors near the top thereof and its opposite end pivoted to one end of the operating lever, a rack secured to the support, a head secured to the operating lever carrying a plurality of latches adapted to engage the rack, a cable secured to the head, and means operable by the cable for disengaging the latches from the rack. 95

8. In an apparatus for opening and closing the door of a building, a support, an 100

operating lever fulcrumed thereon, a link having one end pivoted to the door near the top thereof and its opposite end pivoted to the operating lever, a rack secured to the support, and a head secured to the operating lever carrying a latch adapted to engage the rack, a post outside the building, pulleys mounted thereon, a cable passing over the pulleys and connected to the head, and means operable by the cable for disengaging the latch from the rack.

9. In an apparatus for opening and closing the doors of a building, a support, an operating lever fulcrumed thereon, links each having one end pivoted to the doors near the top thereof and its opposite end pivoted to the operating lever, a rack secured to the support, and a head secured to the operating lever carrying a plurality of latches adapted to engage the rack, a post outside the building, pulleys mounted thereon, a cable passing over the pulleys and connected to the head, and means operable by the cable for disengaging the latches from the rack.

10. In a door operating device, the combination with a lever secured to the door, by a link, of a notched rack mounted adjacent the lever and a head carrying a substantially triangular rocking bar pivoted thereon secured to one end of the lever adjacent the rack and carrying a spring bolt operated in one direction by the spring into engagement with the rack, and in the other direction out of engagement with the rack by the triangular rocking bar which has one corner suitably connected to the bolt.

11. In a door operating device, the combination with a lever secured to the doors

by links, of a notched rack mounted adjacent the lever and a head carrying a substantially triangular rocking bar pivoted thereon secured to one end of the lever adjacent the rack and carrying a plurality of spring bolts each operated in one direction into engagement with the rack by springs and in the other direction out of engagement with the rack by the triangular rocking bar which is suitably connected to the bolts.

12. In a door operating device, the combination with a lever secured to the door by a link, of a notched rack mounted adjacent the lever, a head carrying a substantially triangular rocking bar pivoted thereon secured to one end of the lever adjacent the rack and carrying a spring bolt operated in one direction by the spring into engagement with the rack, and in the other direction out of engagement with the rack by the triangular rocking bar which has one corner suitably connected to the bolt, and a cable operably connected to the rocking bar.

13. In a door operating device, the combination with a lever secured to the doors by links, of a notched rack mounted adjacent the lever, a head carrying a substantially triangular rocking bar pivoted thereon secured to one end of the lever adjacent the rack and carrying a plurality of spring bolts each operated in one direction into engagement with the rack by springs and in the other direction out of engagement with the rack by the triangular rocking bar which is suitably connected to the bolts, and a cable operably connected to the rocking bar.

In testimony whereof he affixes his signature.

JOHN SCHORR.
